DESIGN FOR A DRESS

Mark Cohn, New York, N. Y.

Application September 13, 1938, Serial No. 79,859

Term of patent 3½ years

To all whom it may concern:

Be it known that I, Mark Cohn, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

The design is characterized by the combination on the dress disclosed of the specific braid-like embroidery on the cuff and along the outer central sleeve portions, as shown.

I claim:

The ornamental design for a dress, substantially as shown and described.

MARK COHN.
